UNITED STATES PATENT OFFICE.

FRANCIS M. CAIN, OF WESNER, OKLAHOMA TERRITORY.

METALLIC RAILROAD-TIE.

No. 841,119.

Specification of Letters Patent.

Patented Jan. 15, 1907.

Application filed April 11, 1906. Serial No. 311,126.

To all whom it may concern:

Be it known that I, FRANCIS M. CAIN, a citizen of the United States, residing at Wesner, in the county of Woodward and Territory 5 of Oklahoma, have invented a new and useful Metallic Railroad-Tie; and I do hereby declare the following to be a full, clear, and exact description of the invention, such as will enable others skilled in the art to which it app-10 pertains to make and use the same.

The invention relates to metallic railway-ties, and has for its object to provide a device of this character composed entirely of metal and which will firmly hold the flanges of rails 15 against spreading or being upset when under great strain.

In the drawings forming part of this specification, Figure 1 is a perspective view of one end of a metallic tie constructed in accordance with this invention. Fig. 2 is a longitudinal sectional view. Fig. 3 is a transverse sectional view on the line 3 3 of Fig. 2.

Referring to the drawings, 1 designates the main body of the tie, having an integral jaw 25 2, which coöperates with an adjustable jaw 3 in firmly clamping the base or flange of the ordinary T-shaped rails for either street-cars or railways. The adjustable jaws 3 have side portions or webs 4, which are provided 30 with inwardly-projecting dovetailed tongues 5, which engage dovetailed grooves in the tie. These dovetailed tongues hold the adjustable jaw firmly against vertical movement. The adjustable jaw is held in engagement with 35 the rail by a threaded bolt having a wedge-

shaped portion 6, which when the rail wears loose from continued use can be adjusted to firmly clamp the same.

In practice the tie will rest upon a bar (not shown) laid in a parallel line with the rails, 40 which will render the bolt accessible and which will prevent the tie from sinking into the soft ground or bed.

What I claim is—

1. A metallic railway-tie, having an inner 45 integral jaw, an adjustable jaw coöperating therewith, and a bolt having a wedge-shaped portion engaging said adjustable jaw.

2. A metallic railway-tie, having an integral jaw, an adjustable jaw coöperating therewith, said adjustable jaw having depending side portions, inwardly-projecting tongues formed integral with said side portions and engaging grooves in said tie, and a bolt having a wedge-shaped portion to prevent lateral 55 movement of said adjustable jaw.

3. A metallic tie having an integral jaw and an adjustable jaw, a pair of longitudinal grooves formed in the end portion of said tie, said adjustable jaw being substantially U- 60 shaped and having tongues engaging said grooves, and a bolt having a wedge-shaped portion for preventing lateral movement of said jaw.

In testimony whereof I have hereto affixed 65 my signature in the presence of two witnesses.

FRANCIS M. CAIN.
